UNITED STATES PATENT OFFICE

91,689

DESIGN FOR A HOLDER FOR COLLAPSIBLE TUBES OR SIMILAR ARTICLES

Jacob Herrlich Soeller, Brooklyn, N. Y.

Application November 29, 1933, Serial No. 49,896

Term of patent 7 years

To all whom it may concern:

Be it known that I, JACOB H. SOELLER, a citizen of the United States, residing at 171A Cooper Street, Brooklyn, in the county of Kings, and the State of New York, have invented a new, original and ornamental Design for a Holder for Collapsible Tubes or Similar Articles, of which the following is a specification, reference being had to

the accompanying drawing, forming part thereof.

The figure is a perspective view of the article, showing my new design.

I claim:—

The ornamental design for a holder for collapsible tubes or similar articles, as shown.

JACOB HERRLICH SOELLER.
